UNITED STATES PATENT OFFICE.

EDWIN RUUD, OF PITTSBURG, PENNSYLVANIA, ASSIGNOR TO THE FUEL GAS AND MANUFACTURING COMPANY, OF SAME PLACE.

WATER-HEATER.

SPECIFICATION forming part of Letters Patent No. 443,797, dated December 30, 1890.

Application filed June 21, 1890. Serial No. 356,211. (No model.)

To all whom it may concern:

Be it known that I, EDWIN RUUD, a citizen of the United States, residing at Pittsburg, in the county of Allegheny and State of Pennsylvania, have invented or discovered certain new and useful Improvements in Water-Heaters, of which improvements the following is a specification.

The invention described herein relates to 10 certain improvements in water-heaters for domestic and other purposes, and has for its object a construction of apparatus whereby the flow of gas to the burner may be automatically regulated either to effect an increase or a decrease of the flame by and in 15 accordance with the temperature of the water.

In general terms the invention consists in the construction and combination of mechanical devices or elements, all as more fully 20 hereinafter described and claimed.

In the accompanying drawings, forming a part of this specification, Figure 1 is a sectional elevation of a heater embodying my invention. Fig. 2 is a top plan view, the cap 25 or cover being removed. Fig. 3 is a horizontal section, the section being taken on the line *x x*, Fig. 1, and Fig. 4 is a sectional view showing a modification in the regulating apparatus.

In the practice of my invention a series of 30 tubes or flues 2 are preferably arranged through the shell 1, the ends of said tubes being expanded into the heads 3 3^a in the usual or any suitable manner. This shell is supported at a distance from the floor in any 35 suitable manner, but preferably by extending the shell below the lower head 3^a, as shown in Fig. 1, thereby forming an inclosed box or case for the burner 4. This box or case is provided with a door 5, so as to permit access 40 to the burner, said door having a sheet of mica inserted therein for inspection of the burner. The mixer 4^a is preferably arranged outside of the box or case, and is connected by a pipe 6 to the valve-case 7, to which the 45 gas-supply pipe 8 is also connected. The flow of gas to the burner is regulated by a valve 9, the stem thereof passing up through a stuffing-box 10, and is connected to one end 50 of a lever 11 by means of nuts 12 screwing onto the stem above and below the end of the lever. This lever is pivoted to an arm of the

bracket 13, secured to the shell of the heater, and to the inner end of said lever is attached one end of the expansion rod or tube 14, which is preferably formed of a material having a 55 larger coefficient of expansion than that of the material of which the heater is formed. This rod passes down through a stuffing-box 15, arranged on the upper head 3 of the heater, and through an isolating-pipe 16, arranged 60 within the heater. The lower end of the rod 14 is firmly attached by nuts or other suitable means to the lower head 3^a of the boiler, so that the movements of the rod due to variations of temperature will be limited to its 65 upper free end. The water-supply pipe 18 is connected to the isolating-pipe near its upper end, which is closed by a cap 19, while its lower end is open, thereby causing the water in entering the boiler to traverse said 70 tube before entering the same.

The burner 4, which is preferably circular in contour, is provided on its upper face with a valve disk or plate 20, centrally pivoted, so as to be free to rotate, as hereinafter described, 75 and having perforations adapted when properly shifted to register with the perforations in the burner. This valve-plate is connected by a rod 21 to one arm of a bell-crank lever 22, the other arm thereof being connected by 80 a rod 23 to the lever 11, so that the movement of the lever 11 in opening or closing the valve 9 will so shift the valve-plate as to uncover or cover the perforations in the burner 4. A small burner 24 is arranged over the main 85 burner and is connected by a pipe 25 to the gas-supply pipe 8 at a point outside of the valve 9, so as to provide an igniting-flame for the main burner. In order to provide air for the igniting-flame, the pipe 25 is surrounded 90 by a short tube, one end of which is located outside of the case inclosing the main burner, while the other end is closely adjacent to the burner 24. The heater is provided, as is customary, with an outlet-pipe 26 and a drain- 95 age-cock 27.

In order to avoid the use of a stuffing-box where the rod 14 passes through the head 3, an internally and externally threaded nut 28 is screwed into the head 3, and the tubular 100 rod 14, formed of brass or other metal having a large coefficient of expansion, is screwed

into the nut, as shown in Fig. 4, thereby securing the upper end of the tube to the head 3 of the heater. This tube extends down into the isolating-pipe 16, and within said tube 14 is arranged a rod 29, which is firmly attached at its lower end to the free lower end of the tubular rod 14 by means of a nut 30. The upper end of the rod 29, which is made of iron or some material having a smaller coefficient of expansion than the tubular rod 14, extends up above the head 3 and engages the lever 11. It will be observed that in the construction shown in Fig. 1 the expansion of the rod 14 causes an upward movement of its upper end, whereas in the construction shown in Fig. 4 the expansion of said rod will effect a downward movement of its lower end, thereby pulling down the rod 29. Hence, in order to employ the same construction of valve as shown in Fig. 1, the lever 11 in Fig. 4 is pivoted to an arm 31, attached in any suitable manner to the head 3, and so arranged that the rod 29 engages the lever at a point between its pivot and its connection with the valve-stem.

In using my heater the connections of the stem of the valve 9 and of the plate-valve 20 with the lever 11 are so adjusted that when the water in the heater is at the normal temperature of the supply the valve 9 will be opened and the perforations in the plate-valve 20 register with those in the burner. Said connections are also so adjusted that the expansion of the rods 14, when the water has been heated to a certain predetermined degree, will close the valve 9 and also shift the plate-valve 20, so as to cover the perforations in the burner, thereby preventing a flow of cold air through the mixer and burner and thence through the flues 2. If water be withdrawn from the heater, cold water will flow in through the supply-pipe and passing down through the isolating-pipe will cool the rod 14. The consequent contraction of said rod will open the valve 9 and shift the plate-valve 20, thereby permitting the gas to escape through the burner and be ignited by the constant flame of the burner 24.

It will be observed that by the employment

of the isolating-pipe a more prompt action of 50 the valves 9 and 20 is produced than would be possible if it were necessary to wait for an equalization of the temperature of the entire body of water in the heater. Although it is preferred to employ the isolating-pipe, 55 the operativeness of my device is in no way dependent thereon and it may be omitted.

In order to prevent any injury to the mechanism in case of an excessive movement of the expansion-rod 14, a spring-cushion 32 is 60 interposed between the end of the lever 11 and the lower nut 12.

I claim herein as my invention—

1. The combination of a boiler, a gas-burner arranged below the boiler, a perforated disk 65 arranged over the burner, a valve for controlling the flow of gas to the burner, and mechanism operated by changes of temperature of the water within the boiler for shifting said disk and valve, substantially as set 70 forth.

2. The combination of a boiler, a gas-burner arranged below the boiler, a valve for controlling the flow of gas to the burner, an expansion-rod extending into the boiler and 75 connected at its outer end to said valve, and a pipe surrounding the expansion-rod and connected with the supply-pipe, substantially as set forth.

3. The combination of a boiler, a gas-burner 80 arranged below the boiler, a valve for controlling the flow of gas to the burner, a tubular expansion-rod arranged within the boiler and having its upper end attached to the head of the boiler, a rod 29, having a smaller coefficient of expansion than the tubular rod 85 and arranged within the same, the lower end of the inclosed-rod being attached to the free end of the tubular rod, and a lever connected to the valve-stem and engaging the projecting 90 end of the rod 29, substantially as set forth.

In testimony whereof I have hereunto set my hand.

EDWIN RUUD.
